UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

WELT LAYING AND ATTACHING MACHINE.

1,142,119.

Specification of Letters Patent.

Patented June 8, 1915.

Application filed August 15, 1913. Serial No. 784,908.

To all whom it may concern:

Be it known that I, ADAM H. PRENZEL, a citizen of the United States, residing at Halifax, in the county of Dauphin and State of Pennsylvania, have invented certain new and useful Improvements in Welt Laying and Attaching Machines; and I do hereby declare the following to be a full, clear, and exact description of the invention, such as will enable others skilled in the art to which it appertains to make and use the same.

This invention relates to welt laying and attaching machines and more particularly to such machines adapted to lay and attach a welt to an outsole before it is incorporated in a shoe.

In the manufacture of some types of shoes, known generally as "false welts", in which the shoe is so constructed as to give the appearance of being a "Goodyear welt" although some other method of making it is used, a piece of welting is attached to the margin of the outsole on the flesh side or to the lasted upper, prior to assembling the outsole and upper. In some of these false welt shoes the welting extends merely around the forepart, as in a Goodyear welt shoe, while in others the welting is continuous extending completely around the sole. In making the latter type of false welt shoe which may be termed a "turn welt", some difficulty has been experienced in severing the strip of welting in such manner that the meeting point on the sole between the two welt ends is inconspicuous.

The objects of the present invention are to overcome this difficulty and to insure that a minimum amount of welting is used in attaching a welt on any particular sole.

In accordance with these objects a feature of the invention contemplates the provision, in combination with suitable devices or mechanism for attaching the welting to the outsole, of means for supporting the sole and guiding the welting, and a welt severing device, preferably arranged and operating to sever the welt strip on a bevel, such that the two ends of the portion of the welt attached to the sole will meet and present to the eye a continuous and unbroken grain surface.

A further feature of the invention contemplates the provision of means for indicating to the operative the time at which the welt strip should be severed in order to

use just the amount necessary to produce an exact meeting of the two welt ends and thus avoid waste.

To the accomplishment of these objects and such others as may hereinafter appear, as will readily be understood by those skilled in the art, the invention comprises the features and combinations of parts hereinafter described and then particularly pointed out in the appended claims.

In the preferred form of the invention the welting is secured to the outsole by stitching and this form is illustrated in the accompanying drawings, in which:

Figure 1 is a front elevation of a portion of a sole sewing machine embodying the present invention, showing also a sole in position on the sole supporting table, and a piece of welting being led into position beneath the sole to be secured to its flesh side; Fig. 2 is a side elevation of the parts shown in Fig. 1; Fig. 3 is a detailed view, in plan, of the parts forming the present invention, detached from the sole sewing machine, showing also a sole, marked on its grain side, in position to start the welt attaching operation; Fig. 4 is a detail, in longitudinal section, showing the mounting of the welt severing knife on the sole support, and its operating mechanism; Fig. 5 is a detail, in longitudinal section, through the adjusting devices for accommodating varying widths of welting and for guiding the sole so as to place the line of fastenings relatively nearer to or farther from the edge of the sole; and Fig. 6 is a plan of a turn outsole, having an edge lip cut and upturned, with a continuous welt stitched in the angle between the lip and feather by a sole sewing machine having the present invention incorporated therein.

The machine, in which the present invention has been embodied for the purposes of illustration and explanation, is of the same general type as that shown and described in Letters Patent of the United States No. 473,870, dated April 26, 1892, to The Goodyear Shoe Machinery Company of Hartford, Connecticut, on an application of Z. T. French and W. C. Meyer. The curved hook needle 1, the presser foot 2, the awl 3, the awl segment 4, the upright 5 carrying the awl segment and mounted on the feed slide 6, and the feed changing lever 7 may be, and preferably are substantially as in the

French and Meyer patent above referred to. The shank portion 8 of the work support, that is, the portion by which it is secured on the machine frame, is the same as in said 5 Letters Patent of the United States hereinbefore referred to, but the work support itself has been changed so as to provide a suitable surface for supporting the flat sole to which the welt is to be attached and for 10 housing the knife by means of which the strip of welting is severed. To this end the work support is enlarged in the form of a rectangular block 9 at the right hand end of which, viewing Fig. 1, there is provided, ex- 15 tending in the line of feed, a welt guide 10 (Figs. 2 and 4) over which there is secured, by means of screws, a plate 11 which forms a flat table for supporting the sole. The block 9 is also provided with a dovetailed 20 way 12 (Figs. 1 and 2) extending across the block in line with the needle and awl. In the bottom of this way, at its inner end, is the usual opening 13 (Figs. 3 and 5) for the needle and awl. Seated in the way 12 is a 25 slide 14 (Figs. 1 and 5) having formed therein an aperture 15 above the opening 13 but somewhat wider than said opening, and provided at its inner end with a gage 16 for the edge of the sole and welt. Above 30 the slide 14 is a plate 17 (Figs. 1 and 5) adjustable toward and from the edge gage 16 in the dovetailed way. Both the slide 14 and plate 17 are held fast in any position of adjustment in the way 12 by means of a set 35 screw 18 (Fig. 5). An adjustment of the slide 14 in the way 12 permits the line of stitching, or other welt attaching fastenings, to be placed nearer or farther from the edge of the sole. An adjustment of the plate 17 40 in the way 12 varies the width of opening between the plate and edge gage, thus taking care of different widths of welting. The variation in the widths of the opening 13 and aperture 15 permits adjustment of the 45 slide 14 without interfering with the operation of the needle and awl.

Beneath the sole supporting table 11, and in advance of the awl and needle, there is mounted on the block 9 a support 19 for the 50 welt severing knife. This support is attached to the underside of the block 9 by means of screws 20, and its underside, where it projects above the plane of the block 9, is utilized to form one side of the dovetailed 55 way 12, as best shown in Fig. 1. The support 19 extends downwardly and to the right, viewing Fig. 1, at an angle of about 45 degrees, and on its upper side there is mounted a knife 21. The knife 21 is secured 60 to the support 19 by means of a headed screw 22 passed through a slot 23 in the shank of the knife and threaded into the support. In operation the knife 21 passes through slots formed for its reception in 65 the two walls of the welt guide 10, but it is

normally held in retracted position, as shown in Fig. 4, by means presently to be described. In order to maintain the knife in position to be moved through the slots and across the welt guide it is provided with 70 a guide finger 24, below its cutting edge 25, which slides in a slot formed for its reception in the bottom of the welt guide. This guide finger is never withdrawn from its slot. To further assist in guiding the knife 75 21 in its movement across the welt guide, the support 19 has mounted thereon a plate 26 (Figs. 1, 2 and 4), the upper edge of this plate and the underside of the work table 11 forming a way in which the knife may 80 slide. In order to actuate the knife its shank is provided with a block 27 having formed therein a slot 28 which is engaged by a pin 29 on the underside of one end of a centrally pivoted lever 30, the other end 85 of said lever being elongated into an operating handle 31 (Figs. 1, 2 and 3). The lever 30 is mounted on the support 19 by means of a pivot pin 32 and is normally maintained in the position shown in Figs. 90 3 and 4 by means of a coiled spring 33 surrounding the pivot of the lever and having one end secured to the support 19 and its other end secured to the lever. The movement of the knife 21 toward the left in Fig. 95 4, under the influence of the spring 33, is checked by engagement of the inner end of the slot 23 with the screw 22. On moving the handle 31 of the lever 30, to the left in Fig. 4, the knife 21 is advanced within its 100 guide slots across the welt guide to sever the welt with a beveled cut and on releasing the handle the spring 33 returns the knife to its normal position with the welt guide unobstructed by the knife and free for the 105 passage of the welt therethrough.

Conveniently mounted on the frame of the machine is an arm 34 provided at its upper side with a pin 35 beneath which the strip of welting may be led from the welt 110 reel, or other means for supporting it, on its way to the welt guide 10 and the stitch-forming mechanism. The forward end of the arm 34 is provided with two sole marking devices 36 which are spaced apart a distance equal to the distance between the upper edge of the knife blade 25 and the plane of operation of the needle 1 for a purpose which will be made clear in connection with the description of the operation of the machine.

The presser foot 2, secured to the usual presser foot lever 37, is provided with an enlarged bearing surface, as best shown in Figs. 1 and 3, for holding the sole upon 115 the table 11 as it is fed through the machine past the stitch-forming mechanism. Projecting forwardly from the presser foot across the sole and in the plane of operation of the 120 stitch-forming mechanism, is an indicating 125 130

finger 38 for use in connection with the marking fingers 36 as will now be explained.

In operating the machine to sew a welt completely around a sole, in the manner shown in Fig. 6, the sole is first brought to the marking fingers 36 and its grain side at any desired place, usually at the inside shank, is drawn across these fingers so as to produce two marks on the margin of the sole such as are indicated by the lines *a* and *b* (Figs. 3 and 6). These marks *a* and *b* are used, in the operation of attaching the welt to the outsole, as the starting mark and finishing mark respectively. To attach the welt, the sole, after being marked, is placed on the work table flesh side down, as shown in Fig. 3, with the indicating finger 38 in coincidence with the starting mark *a* on the grain side. The free end of the welt is thrust into the welt guide 10 and positioned below the indicating finger 38, as shown in Fig. 1. The machine is then started and the stitching of the welt to the outsole continued, the work being fed by the awl 3 as usual, until the finishing mark *b* reaches a position of coincidence with the indicating finger 38. At this time the starting mark *a* has reached a position directly over the welt knife 21 owing to the fact that the marking fingers 36 are spaced apart a distance equal to the distance between the knife and the indicating finger. If, then, the operative draws the handle 31 toward him at this time the welt strip is severed just at the point where enough unattached welting is left to exactly fill the space between the finishing mark *b* and the welt end which was first secured to the sole. As a result the two ends of the welt meet and snugly fit when the indicating finger 38 again coincides with the starting mark *a* and the stitching is completed.

The knife 21 is preferably placed at an angle as illustrated, so as to produce a beveled cut and form a joint such as is shown at *c* (Fig. 6) as this type of joint where the two ends overlap is least noticeable, but it should be understood that it is not essential that a beveled cut be made. Those skilled in the art will readily recognize that by means of the marking and indicating devices, described, an exact meeting of the two welt ends can be obtained whatever the nature of the cut and in severing the welt strip may be.

A distinct advantage in the present machine, and an important feature of the invention, is in so manipulating and severing the welt that in the finished sole the grain side of the welt, which is most conspicuous in the finished shoe, is continuous and unbroken at the joint between the two welt ends.

While the present invention has been described as embodied in a machine for stitch-

ing the welt to the outsole, it should be understood that it is not to be limited to attaching the welt by this type of fastening alone, as obviously the invention may be utilized in connection with machines for securing a welt to an outsole by other means than a line of stitches.

The nature and scope of the present invention having been indicated and the preferred embodiment of the invention having been specifically described, what is claimed as new is:—

1. A welt laying and attaching machine, having, in combination, welt attaching mechanism, a sole supporting table, means for feeding a sole and strip of welting past said mechanism, a knife arranged with the plane of its blade at an angle to the face of the sole for severing the welt strip on a bevel, and means for actuating the knife in a right line path transversely of the welt strip to sever it widthwise. 80

2. A welt laying and attaching machine, having in combination, welt attaching mechanism, a sole supporting table, means for feeding a sole and strip of welting beneath the sole past said mechanism, a knife beneath the sole normally retained at one edge of the welt strip, and means for advancing the knife through the welt strip from edge to edge. 90

3. A welt laying and attaching machine, having, in combination, welt attaching mechanism, a sole supporting table, means for feeding a sole and strip of welting beneath the sole past said mechanism, a knife blade beneath the sole angularly arranged relatively to the sole face and provided with a cutting edge at one end, for severing the welt strip on a bevel, and means for advancing the knife widthwise through the welt. 100

4. A welt laying and attaching machine, having, in combination, welt attaching mechanism, a sole supporting table, a welt guide beneath the table having oppositely disposed transverse slots in its side walls forming a guideway, means for simultaneously feeding a sole on the table and a welt strip through the welt guide, a knife movable across the welt guide in said guideway 110 to sever the welt strip widthwise, and means for operating the knife. 115

5. A welt laying and attaching machine, having, in combination, welt attaching mechanism, a sole supporting table, means for feeding a sole and strip of welting beneath the sole past said mechanism, a knife blade beneath the sole provided with a cutting edge at one end angularly arranged relatively to the sole face and in advance 120 of the welt attaching mechanism for severing the welt strip on a bevel, and means for advancing the knife widthwise through the welt. 125

6. A machine for laying and attaching a

welt completely around a sole, having, in combination, welt attaching mechanism, a sole supporting table, means for feeding a sole and strip of welting past said mechanism, a knife for severing the welt strip arranged in advance of said mechanism, means under control of the operative for operating said knife, and means for indicating to the operative the time to operate the knife in order to produce an exact meeting of the two ends of the welt attached to the sole.

7. A machine for laying and attaching a welt completely around a sole, having, in combination, welt attaching mechanism, a sole supporting table, means for feeding a sole and strip of welting past said mechanism, a knife for severing the welt strip arranged in advance of said mechanism, means under control of the operative for operating said knife, a device for marking the sole, and a finger past which the sole is fed for indicating to the operative, when in coincidence with the mark, the time to operate the knife in order to produce an exact meeting of the two ends of the welt attached to the sole.

8. A machine for laying and attaching a welt completely around a sole, having, in combination, welt attaching mechanism, a sole supporting table, means for feeding a sole and strip of welting past said mechanism, a knife for severing the welt strip arranged in advance of said mechanism, means under control of the operative for operating said knife, a device having two marking members spaced apart a distance equal to the distance between the knife and the plane of operation of the welt attaching

mechanism for marking the sole in two places, and a finger for indicating to the operative the starting position of the sole, when in coincidence with one of said marks, and the time to operate the knife in order to produce an exact meeting of the two ends of the welt attached to the sole, when in coincidence with the other of said marks.

9. A welt laying and attaching machine, having, in combination, a table for supporting a flat sole, stitch forming mechanism including an awl for feeding the sole and strip of welting past said mechanism, a welt guide beneath the table, a knife arranged in advance of the stitch forming mechanism, and means for moving the knife widthwise across the welt guide to sever the welt strip.

10. A machine for laying and attaching a welt completely around a sole, having, in combination, a table for supporting a flat sole, stitch forming mechanism including an awl for feeding the sole and a strip of welting past said mechanism, a knife arranged in advance of said mechanism for severing the welt, means under control of the operative for operating said knife, a presser foot, and means including a finger on the presser foot extending across the sole for indicating to the operative the time to operate the knife in order to produce an exact meeting of the two ends of the welt attached to the sole.
